UNITED STATES PATENT OFFICE.

ARTHUR V. EGINTON, OF MERIDEN, CONNECTICUT, ASSIGNOR TO INTERNATIONAL SILVER COMPANY, OF MERIDEN, CONNECTICUT, A CORPORATION OF NEW JERSEY.

DESIGN FOR A CASKET-TRIMMING.

43,337.

Specification for Design.

Patented Dec. 10, 1912.

Application filed September 27, 1912. Serial No. 722,765. Term of patent 7 years.

To all whom it may concern:

Be it known that I, ARTHUR V. EGINTON, a citizen of the United States, residing at Meriden, in the county of New Haven and State of Connecticut, have invented a new, original, and ornamental Design for a Casket-Trimming; and I do hereby declare the accompanying drawing to be a full, clear, and exact illustration of the same, and which said drawing constitutes part of this

application, and represents a face view of a casket-trimming embodying my design.

I claim:

The ornamental design for a casket trimming as shown.

ARTHUR V. EGINTON.
